United States Patent

Des. 240,864

Patented Aug. 3, 1976

240,864

MICROFILM READER

Richard J. Olson, Pittsford, N.Y., assignor to Eastman
Kodak Company, Rochester, N.Y.

Continuation-in-part of design application Ser. No.
379,150, July 13, 1973. This application Feb. 3,
1975, Ser. No. 546,861

Term of patent 14 years

Int. Cl. D16—03

U.S. Cl. D16—14

FIG.1

FIG.4

FIG.3

FIG.2

FIG. 1 is a left front perspective view of a microfilm reader showing my new design;

FIG. 2 is a right side elevational view thereof;

FIG. 3 is a rear elevational view thereof; and

FIG. 4 is a bottom plan view thereof.

This is a continuation-in-part of design application Ser. No. 379,150, filed July 13, 1973.

I claim:

The ornamental design for a microfilm reader, substantially as shown.
